UNITED STATES PATENT OFFICE.

CHARLES MAYER, OF EL PASO, TEXAS.

CAR-BRAKE.

SPECIFICATION forming part of Letters Patent No. 399,764, dated March 19, 1889.

Application filed December 31, 1888. Serial No. 295,024. (No model.)

To all whom it may concern:

Be it known that I, CHARLES MAYER, a citizen of the United States, residing at El Paso, in the county of El Paso and State of Texas, 5 have invented a new and useful Improvement in Car-Brakes, of which the following is a specification.

My invention relates to improvements in car-brakes; and it consists in certain novel 10 features, hereinafter described and claimed.

In the accompanying drawings, Figure 1 is a bottom plan view of a car-truck, showing 15 my improved brake applied thereto. Fig. 2 is a side view of the same, the braces that support the journal-boxes being removed and the ends of the truck-beams being shown in section. Fig. 3 is a detail view showing the manner of supporting the brake-shoe.

Referring to the drawings by letter, A designates the transverse beams of the truck, 20 which are pivotally secured to the under side of the car in the usual manner, and are provided at their ends with the braces B, supporting the journal-boxes C, in which the 25 ends of the axles are mounted.

To the under side of the lower beam A, near the center thereof, I secure the guides D, which receive the inner ends of the vibrating levers E, which are pivoted near their 30 outer ends to the under side of the said beam A. The said levers E are connected to the brake-shoes F by the pitmen G, having their outer ends pivoted to the brake-shoes and their inner ends pivoted to the said levers E 35 on opposite sides of the fulcrum thereof. The inner ends of the levers E are connected by the links H with the lower end of the operating-lever I, fulcrumed on a casting, J, projecting forward from the upper beam A, as 40 shown. The said operating-lever has its upper end connected with the brake-applying devices on the car-platform, as will be readily understood.

K designates a spring having its front end 45 secured to the said lever I and its rear end secured to the lower beam, A, thereby serving to hold the brake-shoes normally off the wheels.

In order to prevent the brake-shoes slipping 50 from the tread of the wheels, I provide the retaining-rods L, which have their outer ends

pivoted to the pitmen G near the brake-shoes, and their inner ends pivoted to the straps M, secured on the under side of the beam A. The brake-shoes are further retained in proper 55 position and supported against the tread of the wheels by the hangers N, having their lower ends pivoted to the brake-shoes and their upper ends mounted upon pivot-rods O, secured in the projecting ends of the metallic 60 strap secured upon the upper side of the lower beam, A.

From the foregoing description it will be seen that I have provided a car-brake in which all the operative parts are arranged 65 beneath the central transverse beams of the car-truck, and are consequently out of the way and not liable to be broken. The usual brake-beams extending transversely between the brake-shoes are dispensed with, and the 70 parts are all very compactly arranged at the middle of the truck. When it is desired to apply the brake, the upper end of the operating-lever is moved toward the beam of the truck, thereby drawing the lower end of said 75 lever away from the said truck, and consequently causing the outer ends of the levers E to be moved so as to apply the brake-shoes to the wheel. Upon releasing the pressure upon the operating-lever the spring K at once 80 returns it to its normal position and releases the brake-shoe from the car-wheel.

Having thus described my invention, what I claim, and desire to secure by Letters Patent, is—

85

1. The combination, with the transverse truck-beam, of the levers pivoted on the under side thereof, the brake-shoes connected to said levers, the operating-lever mounted on the beam, the links connecting the lower end 90 of the same with the inner ends of the pivoted levers, and the spring secured to the operating-lever and the beam, as set forth.

2. The combination, with the transverse beam of the truck, of the levers pivoted to 95 the under side of the same, the brake-shoes, the pitmen connecting the brake-shoes with the levers, the straps M, secured to the beam, the retaining-rods having their ends pivoted to the pitmen and the straps, and devices for 100 operating the levers, as set forth.

3. The combination, with the beam, of the

levers pivoted thereto, devices for operating the levers, the brake-shoes, the pitmen connecting the brake-shoes with the levers, the straps M, secured to the beam, the retaining-
5 rods having their ends pivoted to the pitmen and the said straps, the metallic straps secured to the upper side of the beam, the pivot-pins secured in the ends of said straps, and the hangers having their upper ends mounted on the

10 said pivot-pins and their lower ends pivoted to the brake-shoes, as set forth.

In testimony that I claim the foregoing as my own I have hereto affixed my signature in presence of two witnesses.

CHARLES MAYER.
